Primary Examiner—Ruth McInroy*Attorney, Agent, or Firm*—Ware, Fressola, Van Der
Sluys & Adolphson[57] **CLAIM**

The ornamental design for a shoulder pad assembly for
contact sports, as shown and described.

DESCRIPTION

FIG. 1 is a front elevational view of a shoulder pad
assembly for contact sports showing my new design;
FIG. 2 is a rear elevational view thereof;
FIG. 3 is a top plan view thereof; and,
FIG. 4 is a left side elevational view thereof, the right
side being a mirror image.

FIG.1.

FIG.2.

FIG.3.

FIG.4.
